ADVERTISING SIGN

Lewis E. Peters, Beverly Shores, Ind., assignor to Raymond M. Price & Associates, Inc., Chesterton, Ind., a corporation of Indiana

Application June 1, 1951, Serial No. 15,376

Term of patent 7 years

(Cl. D1—12)

To all whom it may concern:

Be it known that I, Lewis E. Peters, a citizen of the United States of America, residing at Beverly Shores, in the county of Porter and State of Indiana, have invented a new, original, and ornamental Design for Advertising Sign, of which the following is a specification, reference being had to the accompanying drawing, forming a part thereof.

In the drawings:

of Figure 1, taken substantially along the plane of the line 4—4 thereof.

I claim:

The ornamental design for an advertising sign, as shown.

LEWIS E. PETERS.
